UNITED STATES PATENT OFFICE.

THOMAS O. PERRY, OF CHICAGO, ILLINOIS.

DESIGN FOR A WIND-WHEEL.

SPECIFICATION forming part of Design No. 33,010, dated July 24, 1900.

Application filed June 4, 1900. Serial No. 19,083. Term of patent 14 years.

To all whom it may concern:

Be it known that I, THOMAS O. PERRY, a citizen of the United States, residing at Chicago, county of Cook, State of Illinois, have invented and produced a new and original Design for a Wind-Wheel, of which the following is a specification, reference being had to the accompanying drawings, forming a part thereof.

Figure 1 is a front elevation of a wind-wheel 10 of my design. Fig. 2 is an edge elevation showing the wheel as it would appear looking in the direction of the arrow 2 on Fig. 1. Fig. 15 3 is an oblique projection in a plane at right angles to the arrow 2 on Fig. 1. Fig. 4 is a direct endwise view of any one of the sails, looking along the straight lateral edge thereof.

This design is characterized by the following salient features: (a) the three concentric cylindrical thin bands A, A', and A², all contained between two parallel planes at right angles to their common axis; (b) the few and widely-separated longitudinally-radial, transversely-oblique, and concavo-convex sectoral sails B B B, &c., each extending from the band 25 A through the bands A' and A² and terminating radially beyond the last-mentioned band; (c) the form of the sails as seen in direct front elevation of the wheel, such sails being in such direct elevation sectoral, but in a 30 marked degree less-rapidly tapered, widening from the inner to the outer end, than are the sectoral spaces with which the sails alternate and which with such sails make up a complete circle which contains the direct front projection of the wheel, the width of the sail at the band A amounting to approximately three-fourths of the entire circumference, while at the outer ends of said sails they are only about half the circumference of the wheel; (d) the 35 transverse curvature of the sails, which is such that tangents to the curved surface of the sails along the edge located at the side of the wheel toward which the sail is convex make angles with the plane in which all said

edges lie—"plane of the wheel"—which are 45 small and substantially constant or equal throughout the entire length of said edges, while like tangents to said curved surfaces at the opposite edge of the sails make with such plane angles, which increase from the outer 50 extremity of the sails to the inner end of the band A, the rate of increase becoming more and more rapid as the center is approached; (e) the great axial depth relative to the width of the sails B at the inner and narrower extremities, where they join the band A, as compared with their axial depth relative to their width at their outer and wider extremities, the actual absolute depth being substantially the same at the inner and outer 60 ends, while the width of the sails is at the inner end considerably less than half the width at the outer end, and from the features last specified there results a feature somewhat more noticeable to the eye than those mentioned—to wit, that the transverse curvature of the sails rapidly increases from the outer to the inner end, the radius of curvature rapidly increasing from the inner to the outer end; (f) the flanges or lips α α of the bands, 70 which project radially from said bands immediately adjacent to the sails, respectively, along the curved line at which the sails pass through said bands, said flanges being thus located on both the convex and concave sides 75 of the sails.

I claim—

The design for a wind-wheel, herein shown and described.

In testimony whereof I have hereunto set 80 my hand at Chicago, Illinois, in the presence of two witnesses, this 22d day of May, A. D. 1900.

THOMAS O. PERRY.

In presence of—

CHAS. S. BURTON,
ADNA H. BOWEN, JR.
